UNITED STATES PATENT OFFICE.

CHARLES A. NELSON, OF BROOKLYN, NEW YORK.

CIRCUIT-CONTROLLING MEANS.

Original application filed January 27, 1922, Serial No. 532,235. Divided and this application filed June 23, 1924. Serial No. 721,867.

To all whom it may concern:

Be it known that I, CHARLES A. NELSON, a citizen of the United States, residing at Brooklyn, in the county of Kings and State 5 of New York, have invented certain new and useful Improvements in Circuit-Controlling Means, of which the following is a specification.

This invention relates to the class of electric circuit-controlling devices wherein back-and-forth movable means for making and breaking the circuit is impelled to either limit by the action of a spring. One of the principal objects of the invention is to reduce appreciably the noise which attends the action of such devices as heretofore constructed, and at the same time to construct the device so that once the circuit-controlling means has been moved in one direction 10 or the other past a certain position it will automatically continue to the limit of such movement, thus to comply with the fire-underwriters' requirement that in a device of this character the circuit-controller should 15 not be capable of being held by the operator in a position for arcing.

This present application is a division of my application filed January 27th, 1922, Serial No. 532,235.

Fig. 1 of the accompanying drawing shows a circuit-controlling device embodying my invention, the same appearing partly in horizontal section and partly in elevation;

Fig. 2 is a vertical sectional view on the line 2—2, Fig. 1, the moving parts appearing each in true side elevation; and

Fig. 3 is a plan of a certain plate.

a is a supporting structure consisting here 40 of an insulating block formed in two sections, one at the front and the other at the rear, said sections being clamped together by screws *b* which pass through the sections from the rear and are screwed into extension plates or ears *c* bearing against and overhanging at the front surface of the block and provided with holes *c'* to receive screws or the like for fastening the block in a recess *d* in a wall. Between the sections 45 extend the terminals *e* which are to be bridged in closing the circuit, each being secured to the rear section by a screw *f* and equipped with the binding post *g*, access to which for attaching the wiring may be had

by recessing the front section, as at *a'* in Fig. 1.

The block *a* contains a cavity *h* which as viewed in Fig. 1 is generally polygonal, though with concave corners. The opposite surfaces *h'* and *h²* of this cavity form co-acting guiding surfaces or runways as will appear, and in the present example they are slightly concave. It will be preferable to form each surface with a central rib so that there will result two grooves *h³*, spaced from each other by the rib, as shown in Fig. 2. The bottom of each groove *h³* appertaining to the guiding surface *h²* may be formed by the inner end of the corresponding terminal *e*, which 50 extends into the cavity as shown in Figs. 1 and 2.

An elastic circuit-closing member capable of rocking to two reversely inclined positions (in which it coincides with the diagonals of the cavity) is arranged in said cavity, the guiding surfaces *h'* *h²* of which then coact with each other to hold said member in tension as will be explained. In the example this elastic circuit-closing member 55 comprises two roller devices *i* and *j*, each shown as including a spindle *i'* (*j'*) having thereon a pair of rollers *i²* (*j²*) to travel in the grooves *h³*; a stem *k* having a forked bearing *k'* for the roller *j*; a saddle-piece *l* 60 sliding telescopically on the stem and forming a bearing for the spindle of the roller device *i*, which spindle is movable in a longitudinal slot *k²* in the stem, and a spiral spring *m* coiled about the stem and interposed between the saddle-piece *l* and a suitable shoulder on the stem.

Any means for rocking the elastic circuit-closing member may be provided. In the present case I provide for this purpose a 65 lever *n* which projects through a slot *a²* in the block *a* and is fulcrumed on a pin *o* seated in notches *a³* in the block at both sides of the slot, the pin being held in the notches by the top of a boss *p'* (slotted to receive the lever) formed on a plate *p* that is secured to the block by the screws *q*. The boss may be externally threaded to receive a threaded bushing *r* which may serve to hold in place the escutcheon plate *s* shown by dotted lines 100 in Figs. 1 and 2.

The elastic circuit-controlling member is shiftable from the position shown in Fig. 1

in which its roller devices are engaged in two of the diagonally related corners of the cavity to the position in which its roller devices are engaged in the other two such corners. In the position shown it is closing the circuit (roller device *j* being electro-conductive) from one terminal to the other. The guiding surface or runways *h' h** coact with each other to hold said member in tension and they are formed, as shown, to tension the same to substantially the same degree when it is in one of said positions as when it is in the other but to a greater degree when it is in any position intermediate the first two positions. Therefore when force is applied, as by the lever *n*, to shift one end of said member from the end of the corresponding guiding surface which it then occupies toward the other, the said member will undergo increased tensioning and ultimately the opposite end of said member will be automatically sprung from the end of the corresponding guiding surface which it initially occupies to the opposite end, thus instantaneously reversing the position of the circuit-closer proper *j*. Each end of each runway forms a concave rise rising suddenly relatively to the remainder of the runway; further, the periphery of each roller device *i j* forms in effect a convex surface on the member with respect to which the corresponding concave rises are each curved to greater radius. This has two advantageous results: Firstly, when the member is shifted lever-fashion around its point of contact with the lower runway *h** it is impossible for the operator to hold the member in a state of equilibrium or dead-center position and its springing or jumping is instantaneous once it reaches dead-center relation to the actuating lever

n, and, secondly, it assumes the new or reversely diagonal position in the block *a* without the tapping noise that characterizes snap switches heretofore known.

It will be understood that the said member and lever never in practice assume the exact relative positions indicated by Fig. 2 where each is vertical as well as aligned with the other.

Having thus fully described my invention, what I claim as new and desire to secure by Letters Patent is:

1. A circuit-controlling device comprising, in combination, two coacting members one of which is a circuit-controlling member and one of which has a runway and the other a convex surface in contact with the runway and one of which members is also spring-held against the other and spring-urged lengthwise of the runway, said runway having a concave rise rising suddenly relatively to the remainder of the runway but curved to a greater radius than said convex surface in contact therewith.

2. A circuit-controlling device comprising, in combination, two coacting members one of which is a circuit-controlling member and one of which has opposite runways and the other of which is elastic and held compressed between said runways and has opposite convex surfaces respectively in contact with said runways, the latter member being free to shift lever-fashion around its point of contact with one runway and each runway having at each end a concave rise rising suddenly relatively to the remainder of the runway but curved to a greater radius than the convex surface in contact therewith.

In testimony whereof I affix my signature,
CHARLES A. NELSON.
